UNITED STATES PATENT OFFICE

WILLIAM F. WARE, OF BRIDGETON, NEW JERSEY; LYDIA J. WARE EXECUTRIX OF SAID
WILLIAM F. WARE, DECEASED

ROTARY LAWN SPRINKLER

Application filed April 21, 1927. Serial No. 185,516.

My invention has for its object improvements in the sprinkler of my Patent No. 453,005, issued May 26, 1891 to the ends of making the construction better and in some respects cheapening the cost of manufacture and in rendering its action upon the water in distributing it more efficient and otherwise advantageous, all as will appear from the description hereinafter given. My invention 10 consists in whatever is described by or is included within the terms or scope of the appended claims.

In the drawings:

Fig. 1 is a view in vertical section;

15 Fig. 2 is a horizontal section on the line 2—2 of Fig. 1;

Fig. 3 is a perspective view from the underside of the rotary deflector plate;

20 Fig. 4 is a detail section on line 4—4 of Fig. 1.

Referring in detail to what is shown in the drawings, I provide a base member, 10, which in a single cast integral member includes an internally threaded coupling for 25 attachment to a hose or hose stand and a nozzle upon the exterior of which are integral upwardly and outwardly inclined lugs or bosses, 11, preferably four in number, and equi-distant apart, in each of which is embedded the lower end of a substantially L- 30 shape arm or standard, 12, of wire, the upper ends of which are embedded in, and thereby support at a suitable elevation above the nozzle outlet a cap or top member, 35 13, to which as hereinafter explained the rotary deflector plate or wheel is attached. Said top member, 13, comprises a cylindrical, vertical portion, with integral lugs or bosses, 14, that extend at an incline down- 40 wardly and outwardly, in which the upper parts of the standards are respectively embedded. The embedded portions of the standards at top and bottom are non-circular in cross section, preferably elliptical in cross 45 section, and their surfaces are transversely ridged, as by means of mutilated screw threads, so that not only are the embedded portions held from turning in the lugs or bosses in which they are embedded, but a 50 strong, rigid connection is made which gives

the support or framework of the sprinkler a substantial rigid structure, and yet one that is open and light, and inexpensive to make. The embedment of the end portions of the arms or standards is effected by casting, or 55 otherwise.

The rotary deflector plate, 15, is situated between the lower end of the cylindrical portion of the top member, 13, and the top of an inverted cone-shape water distributor, 16, 60 the latter having projecting from its upper side a central shank, 17, that enters a vertical recess in said top member, and which is secured to the top member by a pin, 18, driven transversely through aligning holes in the 65 top member, and an annular groove, 19, in top member, and an annular groove, 19, in the stem, or shank. The rotary deflector plate is thus free to revolve on the stationary shank or stem, and between the upper side of the rotary deflector plate and the bottom 70 of the top member an anti-friction thrust bearing is provided formed by balls, 20, in an annular ball race, consisting of a groove, 21, pressed in the upper side of the deflector plate, and an opposed annular groove in a 75 ring, 22, cast or otherwise secured in the bottom of the top member, 13, said ring preferably being of harder metal than the top member which may be of cast metal. It will be seen that under the upward pressure of 80 water flowing from the nozzle against the underside of the rotary deflector plate, the latter will be lifted from the top of the cone-shape distributor, and thus friction at that point prevented, and the only friction will 85 be the insignificant friction from the upward pressure of the rotary deflector plate against the balls, and thus, even with slight water pressure from the nozzle the rotary deflector plate will rotate and by reason of 90 the water receiving surfaces hereinafter described, there will be a most efficient horizontal spreading or distribution of the water, and, of course, the greater the water pressure the more efficient will the distributing 95 action of the rotary deflector plate be.

A vertical hole, 23, extends from the bottom or apex of the cone-form distributor upwardly through the latter and through its shank, and into alignment with a central hole, 100

24, through the upper part of the top member, 13, that opens out at the top of the latter, so that when the sprinkler is in operation a central fountain will be produced by the jet 5 of water flowing through such aligning openings.

The rotary deflector plate has a form preferably which may be described as a trefoil, and each foil or arm has near its periphery a 10 hole, 25, from which on the underside of the plate a concave lip, 26, extends downwardly and outwardly, and from which on the upper side of the plate a lip, 27, extends upwardly and outwardly, so that the water will flow 15 from the underside of the deflector plate upward and outward in streams in various directions and by the revolution of the rotary deflector plate will be whirled around as well as projected radially outward over a large 20 area.

Adjacent each hole, 25, each foil or arm is bent sharply downward to form a vertical flange, 28, whose vertical surfaces extend tangentially and which by the impact of the 25 water distributed by the cone-shape distributor cause the deflector plate to rotate and the water striking the same to be projected radially outward, and along the lower margin of said flange it is bent horizontally inward 30 to provide a horizontal supplemental flange, 29, which is concave on its upper side, so that water will be deflected thereby upwardly and outwardly, and thus be prevented from being thrown downward to the ground immediately 35 around the stand or support for the sprinkler. The angle of the outwardly projecting portion of the supplemental flange may be changed so that instead of extending upwardly it may extend substantially horizontal, 40 and thus by changing its angle the effect of it upon the water striking it as far as direction is concerned will be modified.

As the distributor cone, 16 is preferably made of soft metal, a bearing, 30, of harder 45 metal is applied to the top, for the rotary deflector, 15, to diminish friction from contact with the underside of the latter.

What I claim is:

1. In a rotary sprinkler, the combination 50 of a frame comprising a base having a nozzle, a top member, standards connecting the base and top member, a rotary deflector plate journaled by the top member, a distributor beneath said rotary plate, and aligning vertical holes through the distributor the 55 rotary plate and the top member, the hole through the top member reaching to the upper end of the latter for the passage of a jet of water, said holes also aligning with the 60 nozzle.

2. A rotary sprinkler comprising a nozzle, a rotary deflector plate, means for supporting the deflector plate above the nozzle, said deflector plate having downwardly projecting flanges which terminate with horizontally in-

wardly projecting supplemental flanges, said flanges and supplemental flanges being in the path of water flowing upwardly against the rotary deflector plate from the nozzle.

In testimony whereof I hereunto affix my 70 signature.

WILLIAM F. WARE.
